UNITED STATES PATENT OFFICE.

HARVEY P. WELLMAN, OF SAN FRANCISCO, CALIFORNIA, ASSIGNOR TO ANDERSON-BARNGROVER MFG. CO., OF SAN JOSE, CALIFORNIA, A CORPORATION OF CALIFORNIA.

CASING FOR HOLDING GOODS CONTAINERS UNDERGOING TREATMENT.

Application filed December 16, 1924. Serial No. 756,330.

To all whom it may concern:

Be it known that I, HARVEY P. WELLMAN, a citizen of the United States, residing in the city and county of San Francisco and

5 State of California, have invented certain new and useful Improvements in Casings for Holding Goods Containers Undergoing Treatment, of which the following is a specification.

10 My invention relates in general to the canning art, and in particular to a special feature thereof which contemplates the provision and use of temporary casings for such goods containers as are unadapted by reason 15 of size, shape or otherwise, for passing through the path of the more common and standard treating machines, apparatus or lines. By making the temporary casings of a size and shape adapted for said treating 20 path, and placing the said goods containers therein, the latter may be run through said path with advantage.

The main object of my invention is to 25 provide a simple and efficient temporary casing for this purpose. This object involves, first, the provision for readily inserting and removing the goods container from the casing; second, the holding of said container against independent movement 30 relatively to the casing; third, the spacing of said container from the casing wall; and fourth, the holding of said container in such position that its end is sufficiently exposed 35 for the action of a leak detector used in connection with the treatment, by which is meant, the method and device now known and in use of detecting leaky cans and separating them from the tight cans by taking 40 advantage of the differential effect of pressure upon the can head in the leaks and tights.

With these objects in view, my invention 45 consists in the novel casing for holding goods containers undergoing treatment, which I shall now fully describe, it being understood that various changes in form, structure and arrangement may be made without departing from the spirit of the invention as defined by the claims herein.

50 In the accompanying drawings, I illustrate the preferable form of my casing.

Fig. 1 is a longitudinal section of the casing, showing the interior holding and

positioning means for an inserted container, the latter being indicated by dotted lines. 55

Fig. 2 is a cross section on the line 2—2 of Fig. 1.

Fig. 3 is a longitudinal section of the casing, showing the interior holding and 60 positioning means further developed to form a stop to limit the insertion of the container in position to have its exposed end approximately flush with the open end of the casing, said container being indicated by dotted lines. 65

Fig. 4 is a cross section on the line 4—4 of Fig. 3.

Fig. 5 is an elevation, partly broken, of a 70 treating vessel, showing its path with casings therein.

1 is a shell which in its best form, to adapt it for accurate and rolling travel in and through the common type of treating path, is cylindrical in cross section and resembles generally both in shape and structure the 75 common forms of cans, being preferably made of sheet metal, rolled and soldered similarly to can bodies. The shell may be fully open at both ends, but in order to stiffen it and also to cause it to approach 80 more closely in outer contour to the ordinary can, whereby it is adapted equally with such can to fit in and roll through the treating path, a head 2 with central opening 3 and rim 4 is soldered to one end. 85

The other end of the shell is fully open, and to said end is soldered an annular ring which provides an exterior bead 5 and an interior downwardly tapering entrance flange 6. 90

Within the shell 1 are fitted means for releasably holding the goods container inserted therein, while passing through the treating path. These means have the function of both holding the inserted goods container against independent movement relatively to the shell, and of spacing it from the shell wall; and to this end such means may be of any suitable nature, adapted in their best form to coact with the tapering entrance flange 6 to permit the ready insertion of the goods container, and to resiliently hold the latter whereby it may be inserted and removed with facility. 95

In the form shown these means consist of 105 a plurality of springy clamp plates 7.

arranged in annular symmetrical series, one vertical edge of each plate being soldered to the shell wall, and the rest of the plate being free and normally standing away from said wall. The edge of each plate adjacent the tapering entrance flange 6 of the shell is flared at 8 to a taper adapted to coact with said flange in readily admitting the inserted goods container.

In Figs. 1 and 2 I have shown in dotted lines fitted to the shell 1, a goods container 9 of general angular shape such for example as a can in which asparagus is usually put up. This container is releasably and resiliently held by the spring clamps 7, so that it has no independent movement relatively to the shell, and is spaced from the shell wall. This results in distinct advantages. Being held relatively to the shell it cannot roll or jostle therein, which would tend to mar its labeled or enameled surface or otherwise injure it; being resiliently held it is not liable to injury; and being spaced from the shell wall it is prevented from receiving such heat therefrom as might tend, in the case of glass containers particularly, to injury due to inequality of temperature.

I refer now to Figs. 3 and 4 for a further elaboration of the holding means within the shell. This is especially adapted for such goods containers as are relatively short and require to be held in the shell with one end exposed approximately flush with the open end of said shell. In these figures I show in dotted lines a small can 10 inserted in the shell 1. This can may represent what is known in the milk processing art as a "baby" can. It is a short can of small diameter as compared with the shell. In this case, means are provided within the shell, in addition to the holding and spacing means, for limiting the insertion of the "baby" can at a point which will present the outer end of the can approximately flush with the open end of the shell. Such means may be of any suitable character, but in their best form they are intimately associated with the holding means, and to this end I slit the inner portion of each clamp plate 7 from the free vertical edge thereof, and thus form the tongues 11, which being bent approximately radially of the shell, towards the axis thereof, with their free extremities overlapping, form a stop for the baby can.

Brace members 12 may be provided to stiff-

fen said stop tongues. Thus the baby can is not only held and spaced from the shell, but is positioned to have one end exposed for the action of the leak-detector as hereinbefore referred to.

In Fig. 5 is shown a treating vessel 13 with a treating path comprising the well known rotating reel rails 14 and helically directed fixed rail 15, and also showing in two instances my casings 1 with their inserted goods containers not shown, in said path.

I claim:—

1. A casing for holding goods containers undergoing treatment, comprising a shell; and an annular series of resilient clamp plates disposed lengthwise and for approximately the depth of the casing interior, each of said plates being secured along one of its sides parallel with the shell axis, to the wall of the shell, the remainder of the plate being free and normally standing away from said wall.

2. A casing for holding goods containers undergoing treatment, comprising a shell having an open end with an inwardly extending tapering entrance flange forming the border of said open end; and an annular series of resilient clamp plates disposed lengthwise and for approximately the depth of the casing interior, each of said plates being secured along one of its sides parallel with the shell axis, to the wall of the shell, the remainder of the plate being free and normally standing away from said wall, and said plates having their edges, adjacent the entrance flange of the shell, tapered to coact with said flange to enter the container.

3. A casing for holding goods containers undergoing treatment, comprising a shell; and an annular series of resilient clamp plates disposed lengthwise and for approximately the depth of the casing interior, each of said plates being secured along one of its sides parallel with the shell axis, to the wall of the shell, the remainder of the plate being free and normally standing away from said wall; and each of said plates having a portion of the inner end bent towards the shell axis to form a stop to limit the insertion of the container.

In testimony whereof I have signed my name to this specification.

HARVEY P. WELLMAN.
